WATER ICE REFRIGERATOR

Clara E. Quinn, Mount Vernon, Ill., assignor to
Broquinda Inc., Wilmington, Del., a corpora-
tion of Delaware

Application March 3, 1937, Serial No. 129,576

4 Claims. (CL. 62—31)

This invention relates to refrigerators of the type employing water ice and is concerned with improvements in the construction thereof which make it possible to attain lower temperatures in the storage spaces from ordinary water ice, to create and maintain proper humidity in the storage spaces, and to secure more uniform temperature conditions therein.

Generally, it may be stated that the mechanism includes a heat exchange wall, in contact with which is placed the water ice on one side and a suitable secondary liquid refrigerant circulating in heat exchange relation with the wall and a heat collecting system exposed to the storage space of the refrigerator. In addition, there is employed mechanism for insuring the presence of the proper amount of moisture in the atmosphere of the storage space while arranging to collect and carry away any condensed moisture.

These and many other objects as will appear from the following disclosure are secure by means of this invention.

This invention resides substantially in the combination, construction, arrangement and relative location of parts, all as will be described in greater detail in the following specification.

In the accompanying drawings,

Figure 1 is a side elevational view of the mechanism comprising this invention within a heat insulated cabinet which is shown in cross-section;

Figure 2 is a cross-sectional view taken on the line 2—2 of Figure 1;

Figure 3 is a top plan view of the inner moisture receptacle; and

Figure 4 is a top plan view of the outer moisture receptacle.

As is well known, the ordinary water ice refrigerator is highly inefficient and it is not possible to reduce the temperature in the storage space thereof to anywhere near the temperature of the water ice. In addition, refrigerators of this type are notoriously inefficient in maintaining anywhere near a uniform temperature within the storage space. The structure of this invention makes it possible to attain much lower temperatures with water ice than is common practice today and to hold these lower temperatures uniformly and at the same time insure the proper humidity in the storage space.

One form of mechanism is illustrated in the drawings and comprises a heat insulated cabinet 1 of any suitable form and construction. Within the cabinet is mounted a shallow metal container 2, which in conjunction with a suitably formed

bottom wall 3 forms a closed circulatory space adapted to contain any suitable and well known form of liquid secondary refrigerant. The wall 3 is preferably made in the form of a series of connected troughs to form a more or less corrugated wall, thereby increasing the area thereof exposed to the convection currents within the cabinet. The wall 3 is sealed to the bottom of the shallow container 2 to produce a series of disconnected and completely closed spaces. These spaces are filled with a liquid, so-called secondary, refrigerant, which is free to circulate therein under the thermosyphonic forces generated. Depending from and connected to the wall 3 in heat exchange relation, by soldering, welding or otherwise, are a series of fins 4 which likewise are corrugated to increase the area thereof. Secured to the lower edges of the outermost fins are a pair of brackets 5 and 6, between which extend and to which are secured a series of small troughs or gutters 7. The brackets are of different lengths so that the gutters 7 all have an inclination towards the back of the cabinet. Supported so as to be below the discharge ends of the gutters is a rectangular tank 8 which is mounted on the back wall of the refrigerator. This container is provided with a discharge spout 9 in the bottom thereof which projects into a waste pipe 10 extending to the exterior of the cabinet.

Within the container 8 is a smaller container 11 of rectangular form which is provided with a discharge or overflow pipe 12 in the bottom wall thereof which extends into the container and above the bottom wall, as is clear from Figures 1 and 2. The spout 12 is positioned so that when the container 11 is placed within the container 8 it discharges into the spout 9. At 14 is a discharge drain pipe for the shallow pan 2 which is positioned so as to discharge onto a baffle 13 secured in the container 11 so as to divert the water discharged from the drain pipe 14 from direct entry into the spout 12. As is clear from the figures, the container 11 is smaller than the container 8 and sits therein spaced from all of its walls.

In the operation of the device, a block of water ice is set in the shallow pan 2 so as to rest on the bottom wall of the pan. The secondary refrigerant is on the other side of this wall and carries the heat absorbed from the storage space and conducted to it by the fins 4 and the wall 3 to the bottom wall of the pan where it gives this heat up to the ice. As the ice melts, the ice water is discharged through the drain 14 into the container 11. The convection currents in the storage space circulate upwardly when heated into

contact with the wall 3 and the fins 4 and give up their heat thereto. Any moisture that collects on the bottom wall 3 and the fins 4 drips into the gutters 7 and runs back into the container 11. By reason of the fact that the spout 12 is above the bottom of the container 11 it will be apparent that a body of water will collect therein until it overflows through the spout. Thus there is always a quantity of water in the container 10 from which evaporation may take place to maintain the humidity in the cabinet. Any moisture which collects on the cold container 11 will drip into outer container 8 and be discharged through spout 9 into the waste 10.

As shown in Figure 1, a shelf 15, which is preferably perforated, as is common practice, is employed to support articles to be refrigerated. With this arrangement it will be apparent that the atmosphere within the insulated cabinet may freely circulate so as to pass in heat exchange relation with the wall 3 and the fins 4. It will be noted that the pan 2 is shown as dividing the ice chamber at the upper part of the cabinet from the storage space.

From the above description it will be apparent that this invention resides in certain principles of construction and operation as illustrated in the drawings, which may be varied by those skilled in the art without departure from the scope thereof. I do not, therefore, desire to be strictly limited to the disclosure as given for purpose of illustration but rather to the scope of the appended claims.

What I claim is:

1. In a water ice refrigerator, the combination comprising a heat insulated cabinet, a shallow metal pan mounted in the cabinet and dividing it into two spaces, said pan being adapted to support a body of water ice, means including a corrugated metal wall sealed to said pan to form therewith a plurality of closed chambers adapted to hold a liquid secondary refrigerant, a plurality of metal fins heat conductively connected to and depending from said corrugated wall, a container having means for maintaining a body of liquid therein, and means for conducting condensate which collects on said fins to said container.

2. In a water ice refrigerator, the combination comprising a heat insulated cabinet, a shallow metal pan mounted in the cabinet and dividing it into two spaces, said pan being adapted to support a body of water ice, means including a corrugated metal wall sealed to said pan to form therewith a plurality of closed chambers adapted to hold a liquid secondary refrigerant, a plurality of metal fins heat conductively connected to and depending from said corrugated wall, a container 10 having means for maintaining a body of liquid therein, and means for conducting condensate which collects on said fins to said container and for conducting the ice water from said pan to said container.

3. In a water ice refrigerator, the combination, comprising a heat insulated cabinet, a shallow metal pan mounted in the cabinet and dividing it into two spaces, said pan being adapted to support a body of water ice, means including a 20 corrugated metal wall sealed to said pan to form therewith a plurality of closed chambers adapted to hold a liquid secondary refrigerant, a plurality of metal fins heat conductively connected to and depending from said corrugated wall, a container 25 having means for maintaining a body of liquid therein, means for conducting condensate which collects on said fins to said container, and a second container within which said first container sits.

4. In a water ice refrigerator, the combination comprising a heat insulated cabinet, a shallow metal pan mounted in the cabinet and dividing it into two spaces, said pan being adapted to support a body of water ice, means including a corrugated metal wall sealed to said pan to form therewith a plurality of closed chambers adapted to hold a liquid secondary refrigerant, a plurality of metal fins heat conductively connected to and depending from said corrugated wall, a container 35 having means for maintaining a body of liquid therein, means for conducting condensate which collects on said fins to said container and for conducting the ice water from said pan to said container, and a second container within 40 which said first container sits.

CLARA E. QUINN.
